Primary Examiner — John Windmuller*Assistant Examiner* — Luqman McNeil(74) *Attorney, Agent, or Firm* — Rothwell, Figg, Ernst & Manbeck PC(57) **CLAIM**

The ornamental design for a remote control, as shown and described.

DESCRIPTION

FIG. 1 shows a right side perspective view of the remote control.

FIG. 2 shows a top view of the remote control.

FIG. 3 shows a bottom view of the remote control.

FIG. 4 shows a right side view of the remote control.

FIG. 5 shows a left side view of the remote control.

FIG. 6 shows a first end view of the remote control; and,

FIG. 7 shows a second end view of the remote control.
